MINING MACHINE CUTTER BIT

Joseph F. Joy, Pittsburgh, Pa., assignor to Joy Manufacturing Company, Pittsburgh, Pa., a corporation of Pennsylvania

Original application October 28, 1948, Serial No. 57,046. Divided and this application April 12, 1954, Serial No. 422,518

7 Claims. (Cl. 262—33)

This invention relates to cutter bits and more particularly to a mining machine cutter bit of the double-ended reversible type.

In cutter bits, and especially those used with the cutter chains of coal mining machines, it has become common practice to place hard metal inserts in the cutting points to increase the resistance to wear. Such hard metal inserts, which are usually composed of tungsten carbide, are usually secured, as by silver soldering or brazing, in recesses in the bit points and such cutting points, due to their brittleness, must be protected against sudden impact with relatively hard objects such as the chain blocks by which they are supported. Further, in cutter bits of the double-ended reversible type it has been found difficult to position the bit with respect to its supporting socket of a chain block so as to provide for the proper bit gauge in the reversed positions of the bit. The present invention contemplates improvements over known types of cutter bits in that the hard metal inserts are so supported and positioned that they are substantially protected against damaging contact with the chain block or other hard object and means is provided for predetermining the bit gauge in either reversed positions of the bit on the chain block.

An object of the present invention is to provide an improved cutter bit. Another object is to provide an improved mining machine cutter bit of the double-ended reversible type. A further object is to provide an improved cutter bit having a hard metal insert set in a novel manner in the cutting point so that the cutting point is substantially protected in either supported positions of the bit on the chain block. A still further object is to provide an improved cutter bit of the double-ended reversible type having improved means for predetermining the bit gauge. Other objects and advantages of the invention will, however, hereinafter more fully appear.

This application is a division of my copending application, Serial No. 57,046, filed October 28, 1948.

In the accompanying drawing there are shown for purposes of illustration two forms which the invention may assume in practice.

In this drawing:

Fig. 1 is a side elevational view of a cutter bit constructed in accordance with the illustrative embodiment of the invention, with the bit shown in operative relation with respect to a conventional chain block.

Fig. 2 is a side elevational view, with a portion in section, illustrating a modified form of cutter bit supported in operative relation to its chain block.

In the embodiment shown in Fig. 1, a double-ended reversible cutter bit 1 is designed for use with a conventional support or chain block of a mining machine cutter chain, as shown in broken lines at 2. The cutter bit has a body formed with relatively inclined arm portions 3 and 4 disposed at an oblique angle and which, at their outer portions, support cutting points or tips 5. The cutting portions have hard metal inserts 6 desirably composed of tungsten carbide and these inserts are secured in recesses

2

7, as by silver soldering, brazing or otherwise, in a well-known manner, as is fully disclosed in my copending application, Serial No. 57,046, referred to above.

The cutting portions 3 and 4 of the cutter bit have parallel front and rear plane surfaces 8 and 9, and projecting rearwardly from the rear surfaces at the apex of the angle, at the rear side of the bit, is an abutment or central projection 10 provided with opposed abutment surfaces 11, 11. The hard metal cutting points are set inwardly with respect to the front faces 8, as shown at 12. The chain block 2 has a right-angle socket 13 for receiving the inactive cutting portion of the bit, and a usual set screw 14 engages the front surface 8 of the inactive portion to hold the rear surface 9 thereof against the rear socket wall. By setting the cutting points inwardly of the plane faces 8 of the bit body the inactive cutting point is protected from engagement with the bit support or block socket walls when the bit is secured in either of its reversed cutting positions on its support or block. The abutment 10 rests on the outer surface of the chain block and serves to limit inward movement of the inactive cutting portion of the bit in the socket and predetermines the projection of the active cutting portion from the block, thereby to provide a predetermined bit gauge.

In the modified embodiment shown in Fig. 2 the improved cutting portions are shown embodied in a double-ended reversible cutter bit 15 which is designed for use with a conventional support or chain block shown in broken lines at 16 and fully disclosed in my copending application, Serial No. 57,047, filed October 28, 1948, now abandoned. The cutter bit has a body formed with relatively inclined arm portions 17 and 18 which, at their outer portions, support cutting points or tips. These arm portions are arranged at an obtuse angle and have plane parallel front and rear surfaces 19 and 20 which intersect along parallel lines, lying in a plane bisecting the bit body at the apex of the angle. These parallel surfaces terminate in cutting portions 21 which provide cutting points or hard metal tips 22 at the opposite extremities of the bit. The cutting portions are formed in the same manner as the cutting portions of the first embodiment and have the same self-sharpening characteristics and improved wear-resisting qualities.

The inactive cutting portion of the bit is receivable in a longitudinally extending socket 23 formed in the chain block and is held in position therein by a usual set screw 24. By setting the cutting points inwardly of the plane faces 19 of the bit body in the manner shown, the inactive cutting point is protected from engagement with the bit support or block socket walls when the bit is secured in cutting position on its cutting support or block.

As a result of this invention, an improved mining machine cutter bit of the double-ended reversible type is provided having an improved arrangement of the hard metal cutting points so that the inactive cutting point is substantially protected against contact with the bit support or block during use, thereby to reduce the possibility of damage to the cutting point. By the provision of the improved abutment at the back of the bit the inward projection of the inactive cutting point within the chain block socket may be limited and the projection of the active cutting point from the chain block may be predetermined, thereby to predetermine the bit gauge. Other advantages of the invention will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A double-ended reversible cutter bit comprising a body having relatively inclined arm portions, said arm portions having plane front faces, the inactive arm portions serving alternately as a support for the active arm portion and receivable in a socket of a bit mounting in either reversed position of the bit, and hard metal inserts set into the opposite ends of said body-arm-portions and providing front cutting tips set inwardly of said front faces whereby an inwardly disposed front face when resting on a socket-wall with the bit in supported position serves to maintain the insert of the inactive cutting tip out of contact with the socket-wall in either reversed position of the bit.

2. A double-ended reversible cutter bit having relatively inclined arm portions terminating in cutting points at the opposite extremities of the bit, said arm portions having relatively inclined front cutting faces terminating in cutting points set inwardly of said front faces, either of said arm portions adapted for insertion in a socket of a chain block and the inactive arm portions serving alternately as a support for the active arm portion with the inactive cutting point out of contact with the socket-walls, and a central projection at the rear side of the bit and providing opposed abutment surfaces disposed at right angles to said cutting faces respectively and adapted for alternate engagement with an outer surface of a chain block thereby to predetermine the bit gauge in either reversed position of the bit, said projection limiting the projection of the inactive cutting face within the block-socket.

3. A double-ended reversible cutter bit having relatively inclined arm portions terminating in cutting points at the opposite extremities of the bit, said arm portions having relatively inclined front cutting faces, either of said arm portions adapted for insertion in a socket of a chain block and the inactive arm portions serving alternately as a support for the active arm portion, and a central projection at the rear side of the bit and providing opposed abutment surfaces disposed at right angles to said cutting faces respectively and adapted for alternate engagement with an outer surface of a chain block thereby to predetermine the bit gauge in either reversed position of the bit, said cutting points having hard metal inserts set inwardly of said arm faces whereby when the inactive cutting portion of the bit is inserted in the block socket the hard metal insert of the inactive point is protected from contact with the socket walls in either bit position, said central projection limiting the projection of the inactive cutting point and its insert within the block-socket with the insert spaced from the socket walls.

4. A double-ended reversible cutter bit comprising a

body having relatively inclined arm portions terminating in cutting points at the opposite extremities of the bit at the same side of the bit-body, the inactive arm portions serving alternately as a support for the active arm portion and receivable in a socket of a bit mounting in either reversed position of the bit, the active arm portion extendable forwardly and outwardly with respect to the bit mounting, and hard metal inserts set into the opposite ends of said arm portions and providing front cutting tips set inwardly of the front faces of the cutting points whereby the front face of the arm portion receivable in the socket of the bit mounting serves to maintain the insert of the inactive cutting tip out of contact with the bit mounting in either bit position.

15 5. A cutter bit as set forth in claim 4 wherein a bit mounting for the bit is provided and said bit has a projection thereon at the side of the body opposite from said cutting points and providing spaced abutment surfaces alternately engageable with a surface of said bit mounting in the reversed positions of said bit for limiting the projection of the inactive bit point within the socket of said mounting.

20 6. A cutter bit and bit mounting as set forth in claim 5 wherein said projection is disposed at the rear side of the bit at the juncture of said relatively inclined arm portions and said surfaces of said projection are alternately engageable with an exterior surface of said bit mounting.

25 7. A double-ended reversible cutter bit comprising a body having relatively inclined arm portions, said arm portions serving alternately as a support for the active arm portion with the inactive arm portion receivable in a socket of a bit mounting in either reversed position of the bit, said arm portions having plane front faces and terminating in cutting tips set inwardly of said front faces whereby an inwardly disposed front face, when the bit is received in the socket of the bit mounting with the plane face of the inactive arm portion resting against the wall of the socket, serves to maintain the inactive cutting tip out of contact with the socket-wall.
